FRIEDRICH M. LUCHS, OF PITTSBURGH, AND FREDERICK W. KOEHLER, OF WILKINSBURG, PENNSYLVANIA, ASSIGNORS TO AMERICAN ATMOS CORPORATION, OF PITTSBURGH, PENNSYLVANIA

BREATHING APPARATUS

Application filed August 12, 1929. Serial No. 385,154.

Our invention relates to breathing apparatus, and more particularly to the mechanism within and attached to the flexible breathing bag for the simultaneous control of high pressure oxygen from an oxygen bottle into an expansion chamber and the release of the expanded gas into the bag.

It comprises a single operating lever automatically actuated by the collapse of the breathing bag, which member controls the opening of two valves one from the expansion chamber to the bag, and the other from high pressure source into the expansion chamber. The control is positive, mechanical and direct, and prevents sticking of the parts, permits a structure wherein the valves will not foul by exhalation products, and is all contained in a single fitting outside, but close to the breathing circuit.

Other features of the invention and details of construction will hereinafter be described and claimed.

Referring to the drawings, in which like parts are similarly designated—

Figure 1 is a vertical section of one form of construction.

Fig. 2 is a spider to which the connecting springs of the lever arm are secured.

Fig. 3 is a plate for attaching these springs centrally to the lever.

Fig. 4 is a front view of the valve controlling discharge from the expansion chamber.

Fig. 5 is a vertical section of a simplified form of apparatus.

Fig. 6 is an elevation of the operating lever and fitting.

Referring to Figure 1, one wall 10 of the bag is fixed to a supporting frame of the breathing apparatus and its opposite wall 11, which is relatively movable, is connected to the relatively stationary wall by the flexible rubber fabric 12, bellows-like.

This construction and form of breathing bag is well known.

A round hole is cut in such a bag near its bottom in which is inserted a fitting A forming the expansion chamber and having a marginal flange 13, while on the interior of the bag is a securing ring 14 held against the

flange with the fabric between them, and secured together by screws, rivets or the like, as 15, in Fig. 6. At the bottom of the fitting, outside of the bag is a screw nipple 16 for connecting an oxygen bottle to the device. A packing washer 17 insures against leakage, and a valve seat 18 with a small hole through it, enters the fitting.

Within the fitting is a bell-crank lever 19 loosely mounted on a pin 20. Alined bores 21 and 22 are closed by the larger threaded end 23 of the pin 20. A coil spring 24 surrounds the pin 20 between one side of the lever 19 and the head of the pin.

A valve closure 25 of non-combustible material is seated in the horizontal arm of the bell-crank lever 19, and has a hole 26 through the arm to enable the closure to be driven out of the arm and be replaced. The other, vertical, arm of the bell crank lever has a grub screw 27 passing through it and is urged by a coil spring 28 in the direction of opening of the oxygen valve to prevent sticking. A screw plug 30 is in a hole in line with screw 27 for the insertion of a screw-driver, for adjusting the screw.

The inner end of the screw 27 passes through a hole 31 in a thin sheet metal disc 32 or closing wall for the expansion chamber, and is held in a recess in the inner face of the fitting by a screw ring 33.

Soldered, brazed or otherwise secured to the disc 32 is a flexible metal flap 34 covering the hole 31 in the disc and engaged by the end of screw 27. Engaging the opposite face of flap 34 is the short arm of an actuating lever 35 mounted on a pin 36 held in lugs 37 extending from ring 14.

Loosely passing through the lever 35 is a screw 38 whose head limits the swing of the lever to the left, as shown, and whose threaded end screws into the ring 14 as a grub screw. Alined with the screw 38 is a locking screw 39 provided with a sealing washer 40 and passing through the flange 13.

By removing the locking screw 39, which is on the outside of the bag, the lever limiting screw 38, which is inside the breathing bag, can be adjusted by inserting a screw-driver in its slotted or grub screw end to adjust the

limit of swing of the lever 35 to the left, and thereby the pressure of plug 25 on the oxygen nozzle or seat 18. This lever 35 is moved from the relatively movable wall 11 of the bag, for which purpose it carries on its outside a three-armed spider 41, through the ends of whose arms pass screw studs 42 held by nuts 43 on the inside of the bag and having holes 44 through which one end of three coil springs 45 pass respectively. The other ends of these springs are connected to a sheet metal connector plate 46, Fig. 3.

The plate 46 is loosely mounted on a bolt 47 in the end of the longer arm of lever 35. The connector plate 46 preferably has slight longitudinal play on the bolt 47, as shown.

The adjusting screw 38 may or may not have a coil spring surrounding it between the lever and the ring 14, as spring 48.

20 The operation is as follows:

As the oxygen content of the bag is consumed and converted into carbon dioxide by the wearer and removed from circulation by the usual regenerator, the volume of respirable gases is decreased, the bag collapses, the movable wall 11 moving toward lever 35 and moving the lower, shorter arm away from the flap 34. The screw 27 acting on the opposite side of the flap follows up this movement by reason of spring 28 acting on bell-crank lever 19, which opens the oxygen control valve 25, 18, admitting oxygen into the expansion chamber and thence through the hole 31 past the flap 34 into the bag.

35 As the bag distends the movable wall 11 moves away from the lever 35 and the springs 45 pull the lever with them to close the flap and re-seat the oxygen valve until the lever rests against and is stopped, by the head of screw 38.

If spring, as 48, Fig. 5 is also used in this construction the lever is considerably steadied.

A slight, further distension of the bag is 45 permissible by reason of the springs 45 which permit the movable wall of the bag to respond to respiratory movement while holding the valves closed.

In Fig. 5 the structure is similar to Fig. 1, 50 but the lever 35^a is not connected to the movable wall 11. This wall has a plate 50 inside the bag that moves against the end of the lever, and the tension in the bag is controlled by a spring 51 connected at one end to the 55 plate and having at its other end a screw 52 outside of the bag on the relatively stationary wall 10. The screw is provided with a nut 54 and a gas-tight washer 55.

In this construction the lever 35^a is urged 60 to closing position solely by coil spring 48. In other respects the construction is like that of Fig. 1.

We claim—

1. The combination with a breathing bag; 65 of an expansion chamber mounted on one

wall thereof, a valve in said chamber to admit high pressure gas thereto for expansion therein, a low pressure valve to admit expanded gas from the chamber into the bag, and an operating lever actuated by the movement of a wall of the bag to operate the low pressure valve and said valve directly and mechanically operating the high pressure valve.

2. The combination with a breathing bag; 70 of an expansion chamber mounted on one wall of the bag, a flap valve controlling the admission of expanded gas from said chamber to said bag, means to open and close the valve, a high pressure valve in the expansion chamber comprising a seat and a closure therefor, said closure being operated from the flap of the flap valve.

3. The combination with a breathing bag; 75 of an expansion chamber, a metal closure for the chamber, a flexible flap covering a hole in said closure, a bell-crank lever in the expansion chamber, one arm of which contacts with the flap, a valve closure on its other arm, a valve seat engaged by said closure, 80 said seat being arranged for connection to a source of high pressure gas, and means dependent on the movement of a wall of the bag for controlling the flap and thereby the operation of said bell-crank lever and valve closure carried by it.

4. The combination with a breathing bag; 85 of an expansion chamber, a metal closure for the chamber, a flexible flap covering a hole in said closure, a bell-crank lever in the expansion chamber, one arm of which contacts with the flap, a valve closure on its other arm, a valve seat engaged by said closure said seat being arranged for connection to a source of high pressure gas, means dependent on the 90 movement of a wall of the bag for controlling the flap and thereby the operation of said bell-crank lever and the valve closure carried by it, and a device to limit the movement of said means to prevent undue pressure on 95 said flap and closure.

5. The combination with a breathing bag; 100 of an expansion chamber, a closing member for the chamber having a hole therein, a flexible flap covering the hole, a lever in the chamber arranged for operation by said flap, a high pressure gas valve closure on said lever; 105 means to adjust the lever relatively to the flap, and means to operate the flap and thereby by the lever.

6. The combination with a breathing bag; 110 of an expansion chamber, a closing member for the chamber having a hole therein, a flexible flap covering the hole, a lever in the chamber arranged for operation by said flap, a high pressure gas valve closure on said 115 lever, means to adjust the lever relatively to the flap, means to operate the flap and thereby the lever, and a spring in the chamber to urge 120 the lever, and a spring in the chamber to urge 125 the lever, and a spring in the chamber to urge 130

the lever into opening position of the closure and flap.

7. The combination with a breathing bag; of an expansion chamber on one wall of said bag, a closure for the chamber having a hole therein to the interior of the bag, a flexible flap covering the hole, a lever in the chamber, an adjusting screw in one end of the lever passing through said hole and engaging the 10 flap, a spring between said lever and a chamber wall, an aperture in the chamber alined with said screw, a plug for said aperture, a valve closure on the lever, an operating lever in the bag engaging the flap in line with said screw, and limiting means for the operating lever.

8. The combination with a breathing bag having a movable wall; of an expansion chamber for the bag, a flap valve between the 20 chamber and bag, an operating lever whose short arm controls the valve, a spider on the movable wall, coil springs in the bag each connected at one end of a spider arm, a connecting plate to which all of the springs are 25 fastened, means connecting the plate and lever, and limiting means for the lever.

9. The combination with a breathing bag having a movable wall; of an expansion chamber for the bag, a flap valve between 30 the chamber and bag, an operating lever whose short arm controls the valve, a spider on the movable wall, coil springs in the bag each connected at one end of a spider arm, a connecting plate to which all of the springs are 35 fastened, means connecting the plate and lever, limit means for the lever, said limit means arranged inside the bag and adjustable from the outside of the bag.

10. The combination with a breathing bag; of an expansion chamber mounted on the bag, a flap valve between the chamber and bag, an operating lever in the bag operated by collapse of the bag to release said flap valve, a screw loosely passing through the lever and 45 having a head to limit the movement of the lever and a slotted end, an alined locking screw operable from the outside of the bag to engage the aforesaid screw, and a coil spring surrounding the latter screw to urge 50 the lever.

11. The combination with a breathing bag having relatively stationary and movable walls; of an expansion chamber mounted in the stationary wall, a sheet metal cover for 55 the chamber having a hole connecting the chamber and interior of the bag, a flexible flap for said hole, a lever in the chamber, an adjusting screw in the lever passing through said hole and engaging the flap, a high pressure gas closure on the lever, a spring to urge the lever to open said closure, an opening in the chamber in line with said screw, a closure for the opening outside the chamber, an operating lever pivoted to the chamber inside 60 the bag, a headed screw loosely passing

through the lever and a locking screw alined with the headed screw and removable from the outside of the bag, said operating lever actuated by the movable wall of the bag.

In testimony that we claim the foregoing as 70 our invention, we have signed our names hereto.
